(57) CLAIM

The ornamental design for an objective gunner protection kit, as shown and described.

DESCRIPTION

The invention described and claimed herein may be manufactured, used, and licensed by or for the U.S. Government for U.S. Government purposes.

FIG. 1 is a perspective view of a gunner protection enclosure showing our new design;

FIG. 2 is a second, close-up perspective view thereof;

FIG. 3 is a front elevation view thereof;

FIG. 4. Is a rear elevation view thereof;

FIG. 5 is a left side elevation view thereof;

FIG. 6 is a right side elevation view thereof; and,

FIG. 7 is a top plan view thereof.

The broken lines shown in the Figures depict unclaimed subject matter only and form no part of the claimed design.
